CONTROL APPARATUS

Russell B. Matthews, Wauwatosa, Wis., assignor, by mesne assignments, to Penn Controls, Inc., Goshen, Ind., a corporation of Indiana

Filed Mar. 25, 1957, Ser. No. 648,415
8 Claims. (Cl. 158—123)

This invention relates to control apparatus and more particularly to apparatus wherein several control devices are interlocked to require operation of one of such devices prior to operation of the other.

More specifically, the present invention pertains to temperature control apparatus having temperature varying means including control means therefor, fan means for circulating air at said temperature varying means, and means interlocking said fan means and the control means for said temperature varying means requiring satisfactory operation of said fan means prior to commencement of operation of said temperature varying means.

It is therefore an object of this invention to provide control apparatus having two electrically energizable devices and means interlocking said devices to require energization of a given one of such devices prior to energization of the other.

Another object is to provide control apparatus as characterized above wherein the first device to be energized is electrically driven fan means and the other device is self-powered temperature varying means.

Another object is to provide temperature control apparatus as characterized above wherein the self-powered temperature varying means comprises a main fuel burner and an ignition burner therefor, and a thermoelectric generator responsive to a flame at said ignition burner to effect safety shut-off of said main burner upon outage of the ignition burner flame.

Another object is to provide control apparatus as characterized above wherein the thermoelectric generator comprises at least one semi-metallic thermoelement.

Another object is to provide in control apparatus having a main fuel burner and fuel flow control means therefor, an electrically driven fan means for circulating air at said main burner, a thermoelectric generator in circuit with said main burner fuel flow control means and electroresponsive heating means energized by the source of power for said fan means to effect heating of one of the junctions of said generator, whereby said control means is operable to permit fuel flow to said main burner only if there is power available for said fan means.

Another object of this invention is the provision of control apparatus comprising electrically driven fan means and a source of power therefor, a main fuel burner and an ignition burner therefor, a main burner fuel flow-control device having two cooperating electromagnetic windings, a first thermoelectric generator in circuit with one of said windings for energization thereof in response to a flame at said ignition burner, and means including a second thermoelectric generator in circuit with the other winding and heating means for one of the thermojunctions of said second generator energized from the source of power for said fan means to cause said second generator to energize said second winding, whereby fuel is permitted to flow to said main burner only when a flame exists at said ignition burner and power is available for operation of said means.

Another object is to provide control apparatus as characterized above, including means operatively associated with said first thermoelectric generator to cause said first generator to reverse the polarity of its output upon cooling as by outage of the ignition burner flame.

Another object is the provision of control apparatus as characterized above wherein the main burner fuel flow-

2

control device is of the electromagnetic type and wherein said second thermoelectric generator and its associated electromagnetic winding develop appreciably more ampere-turns than said first thermoelectric generator and its associated electromagnetic winding whereby termination of said output of said second generator as by failure of the power source for said fan means effects a decrease in the ampere-turns in said flow-control device sufficient to cause interruption of main burner fuel flow, there being means associated with said first thermoelectric generator to cause reversal of polarity of the output thereof upon cooling and decrease in the ampere-turns in said flow-control device also sufficient to effect interruption of main burner fuel flow.

15 The novel features which I consider characteristic of my invention are set forth with particularity in the appended claims. The device itself, however, both as to its organization and mode of operation, together with additional objects and advantages thereof will best be understood from the following description of specific embodiments when read in connection with the accompanying drawing, in which:

20 The single figure is a schematic showing of an embodiment of the present invention, some of the components of the apparatus being shown in section.

25 Referring to the drawing, the embodiment selected for illustration comprises a fluid flow-control device 8 having a valve body or housing 10 formed with an inlet chamber 12 and an outlet chamber 14 connected to contiguous sections of a main burner fuel supply conduit 16. A partition wall 18 formed with a valve seat 20 is provided in body 10 for separation of inlet 12 and outlet 14. Conduit 16 extends through a suitable opening in a wall of a heating unit 22 for supply of fuel to a main fuel burner 24 through a mixing chamber 26. Main burner 24 is positioned within a combustion chamber 28 of heating unit 22, there being an exhaust chamber 30 in communication with combustion chamber 28 and a bonnet or plenum chamber 32 in heat exchange relation therewith.

30 40 A valve operator housing 34 is fixed to control body 10 over an opening in the upper wall thereof, there being a movable partition or flexible diaphragm 36 fixed therebetween about its marginal edge. Sealing means such as gaskets 38 and 40 are installed on opposite sides of the marginal edge of diaphragm 36 to prevent escape of fluid fuel. Such positioning of diaphragm 36 provides a pressure chamber 42 on the side thereof within housing 34 while the other side thereof is exposed to the fluid pressure at inlet 12.

45 50 Fixed to diaphragm 36 by means of a stud 44 and a nut 46 is a control member in the form of a valve disc 48 which is movable with diaphragm 36 between flow-permitting and flow-preventing positions with respect to valve seat 20. A back-up plate or reinforcing member 50 overlies diaphragm 36 and is clamped thereagainst by means including stud 44 and nut 46. Back-up plate 50 functions as a stiffening member for the diaphragm and as a biasing weight for purposes to be hereinafter set forth. Plate 50 also serves to define the effective area of diaphragm 36 as is well understood in the art.

55 60 Positioned within operator housing 34 on a mounting member 52 is an electroresponsive valve operator 54 comprising an electromagnet core member 56 mounted on member 52 and first and second energizable means such as electromagnetic winding 58 and electromagnetic winding 60. Operator 54 further comprises a mounting bracket 62 fixed to member 52 and formed with a dished or cup-shaped end portion 62a. An actuating or control member 64 is pivotally mounted with respect to bracket 62 by means of a pivot screw 66 formed with a conical end portion 66a for cooperation with the dished end portion 62a of mounting bracket 62. Pivot screw 66 has an

end portion 66b formed with a screw driver kerf to facilitate adjusting the position of screw 66 with respect to lever 64, a lock nut 68 being provided for retaining pivot screw 66 in any desired position. A helical tension spring 70 having one end fixed to an extent 62b of bracket 62 and its other end fixed to lever 64 is provided to bias lever 64 in a counterclockwise direction about its aforementioned pivot or fulcrum.

Fixed to actuating lever 64 by means of a screw 72 is an armature member 74 for cooperation with magnet 10 core member 56 as will hereinafter appear.

A valve member 76 adjustably fixed to actuating lever 64 by means of a threaded valve stem 78 and a cooperating lock nut 80 is provided for flow-control cooperation with a tubular bleed port member 82 threadably fixed to mounting member 52.

Affording communication between inlet chamber 12 and pressure chamber 42 is a fluid passageway 84 formed by aligned openings in valve body 10, diaphragm 36, gaskets 38 and 40, and operator housing 34. A bleed passage 86 is formed by aligned openings in housing 34 and mounting member 52 and is afforded communication with the through opening in tubular bleed port member 82 by means of a plate 88 sealingly fixed in spaced relation to mounting member 52 by means such as screws 90 and gasket 92. A bleed conduit 94 having communication with bleed passage 86 has its free end positioned adjacent main burner 24 within combustion chamber 28. The portions of the pressure chamber above and below the mounting member 52 are in free communication as, for example, through an opening 52a in said member.

Extending through a suitable opening in the side wall of combustion chamber 28 of heating unit 22, is a pilot or ignition burner 96 which, as shown schematically by line 98, is afforded fluid fuel supply independently of the aforescribed control device 8. As is well understood by those persons skilled in the art, ignition burner 96 is positioned to afford ignition of main burner 24 and heating of a thermoelectric generator 100 positioned within an opening in the side wall of combustion chamber 28. Generator 100 is so positioned with respect to combustion chamber 28 as to have one of its thermojunctions adjacent ignition burner 96 for heating by a flame thereat, and another of its thermojunctions outside of combustion chamber 28 to be substantially independent of temperature changes therewithin.

Thermoelectric generator 100 comprises a pair of thermocouple element means 102 and 104, the latter of which takes the form of an elongated generally cup-shaped sheath member, preferably of stainless steel. The sheath 104 has a tubular sleeve portion 106 and a tip portion 108. The opposite end of the member 104 is telescopically received within a counterbore formed in one end of an extension tube 110 of brass or similar material and is sealingly fixed therein, as by silver soldering or brazing at 112. The other end of tube 110 is formed with a portion of reduced diameter to snugly receive one end of a coaxial type thermoelectric generator lead 114 comprising metallic tubular outer conductor 116 and insulated coaxial inner conductor 118. The sleeve 110 has an end recess adjacent the lead 114, and said tube and lead are sealingly and electrically connected, for example, by silver soldering or brazing at 120.

The thermocouple element means 102 preferably comprises a rod-like or cylindrical ingot of semi-metallic alloy or composition disposed in coaxial spaced relation within a sheath 104. Because the thermocouple element means 102 is of frangible material, the generator 100 is constructed in a manner to provide shock resistant mounting means therefor. The element means 102 includes a contact electrode 122 having a stem portion 124 and a shoulder 126. The tube 110 is formed with an internal annular shoulder 128 and surrounding the contact electrode stem portion 124 is an insulating washer 130 engaging the shoulder 128. Interposed between the insulating washer

130 and the stem shoulder 126 is a compression spring 132 which may take the form of a concavo-convex centrally apertured resilient disc also surrounding the electrode stem 124. The sheath 104 is formed with a conical end wall 134, and the semi-metallic element 102 is formed with a complementary conical end wall 136 which is seated against the end wall 134 to provide a thermojunction which hereinafter will be referred to as a hot junction. The spring 132 exerts compressive stresses on the element 102, which stresses substantially reduce the net tensile stresses to which said element is subjected during transverse acceleration or shock, said compressive stresses not being so high as to exceed the compressive strength of said element. The bias of spring 132 also provides the pressure necessary for a satisfactory pressure contact between the element 102 and the sheath 104 at the hot junction. The pressure type contact is not deleteriously affected by deformation of the element 102, for example, on bending under transverse shock, and the conical nature of the surfaces 134 and 136 tends to maintain element 102 in centered relationship within the tubular portion 106 of the member 104. The compressive stress under which the member 102 is placed increases the magnitude of deformation which said element can withstand without fracture and affords the generator 100 substantial shock resistance.

A tube 138 of insulating material preferably surrounds the contact electrode stem 124, and a flexible conductor 140 extends within the tube 138 and affords an electrical connection between the stem 124 and the inner conductor 118 of the coaxial lead 114.

Fixed to the sheath member 104 of generator 100 is a tubular heat conducting member 142 having an inner diameter substantially larger than the outer diameter of sheath 104. Tubular member 142 is provided with an inside diameter substantially larger than the outside diameter of sheath member 104, one end of said member 142 being of reduced size to closely fit sheath member 104 intermediate the length thereof. Member 142 is of sufficient length to prevent a flame at ignition burner 96 from touching the sheath 104.

Thermoelectric generator 100 is connected in circuit with electromagnetic winding 58 of valve operator 54, the inner conductor 118 of coaxial lead 114 being in circuit with a terminal member 144 insulatably positioned within a suitable opening formed in operator housing 34. One end of winding 58 is connected to terminal member 144 while the other end thereof is in circuit with operator housing 34 by electrical connection thereof to mounting member 52. The outer conductor 116 of lead 114 is connected to operator housing 34, a coaxial lead connector tip (not shown) preferably being threadably secured within a suitably formed receptacle 146 on housing 34 to effect connection of the inner and outer conductors with the various other circuit components.

Positioned adjacent plenum chamber 32 of heating unit 22, is an electrically driven blower or fan means 150 for circulating the air within chamber 32 by forcing the same to the area to be heated by main burner 24. Connected to electrically driven fan means 150 are lead wires 152 and 154 which conduct electrical energy to fan means 150 from a source of alternating current electrical energy schematically shown at 156.

Interconnecting the alternating current source at 156 and the control device 8, is interlock means comprising a thermoelectric generator 200 which is substantially identical with the aforescribed generator 100. The components of generator 200 which are identical with corresponding components of generator 100 are identified in the drawing with numerals in the 200 series, the last two digits of each numeral being the same as the last two digits of the 100 series numeral used to identify the same or identical component of generator 100. In view of this, it is believed that reference may readily be made

to the description hereinbefore set forth of generator 100 for all of the components of generator 200, wherefore a detailed description of such generator components will not now be repeated.

A lead wire 300 affords connection of the inner lead 218 of coaxial lead 214 with a terminal member 302 insulately positioned within a suitable opening in housing 34. Other conductor 216 of lead 214 is connected to housing 34 by means of a lead wire 304 having a condition responsive switch 306 connected intermediate the length thereof. Lead wires 300 and 304 preferably are inner and outer conductors respectively of a coaxial lead, in which event, electrical connection of lead wires 300 and 304 with terminal member 302 and housing 34 respectively may be made through a coaxial lead connector tip (not shown) threadably secured within a suitably formed receptacle 308 in housing 34. The electrical circuit to winding 60 is completed by connection of one end of said winding 60 to terminal 302 and the other end thereof to mounting member 52.

The condition responsive switch 306 selected for illustration in the drawing comprises a stationary contact 310 fixed to one section of lead wire 304 and a bimetal element 312 connected to the other section of lead wire 304 and carrying a movable contact 314 for circuit controlling cooperation with stationary contact 310 upon deformation of bimetal element 312 with changes in ambient temperature thereat. I prefer to locate switch 306 in the space or area to be afforded heat by main burner 24 so as to provide thermostatic control as will hereinafter appear.

Fixedly positioned on sheath member 204 of thermoelectric generator 200, is an electroresponsive temperature affording device 316 comprising an electric heating coil 318 for varying the temperature of the generator thermojunction afforded by conical surfaces 234 and 236. One end of coil 318 is connected to lead wire 152 and the other end of coil 318 is connected to lead wire 154, thereby placing said coil 318 directly in circuit with the source of alternating current shown at 156.

In order to obtain optimum operation of the apparatus hereinbefore described, I prefer to construct thermoelements 102 and 202 of thermoelectric generators 100 and 200 respectively in a particular manner. That is, either or both of elements 102 and 202 may, for example, be formed of an alloy described in the Robert W. Fritts and Sebastian Karrer Patent No. 2,811,571.

Mechanical and electrical contact between the thermocouple elements 104 and 204, and the semi-metallic thermocouple elements 102 and 202, respectively, is made over a substantial area by the pressure contact between the surfaces 134 and 136 and between the surfaces 234 and 236 respectively. Contact with the opposite ends of the elements 102 and 202 is made over substantial areas thereof to the contact electrodes 122 and 222. Such contact electrodes provide contacts of low thermal and electric resistance, and are chemically stable with respect to the elements 102 and 202. As more fully described in Russell E. Frederick, Robert W. Fritts and William V. Huck Patent No. 2,811,569, iron is especially adapted for use as contact electrode material with lead-tellurium-selenium compositions.

It will be noted that when the tips 198 and 208 of the sheaths 104 and 204 are heated, the elements 102 and 202 are free to expand and the flexible conductors 140 and 240 maintain continuity of the respective electrical circuits between the electrodes 122 and 222 and the lead conductors 118 and 218 while at the same time affording means for isolating said electrodes and the elements 102 and 202 from external forces which might be applied to the leads 114 and 214.

Since, as is well known in the art, the electrical and thermal resistance of the thermoelectrical generators are dependent upon the configuration thereof, as well as on the electrical and thermal conductivities of the elements

102 and 202 and sheaths 104 and 204, a relationship between the dimensions of the elements and sheaths can be obtained which affords the highest thermal conversion efficiency in such a mounting or assembly. In the 5 embodiments described, the thermal conductivity of the elements 102 and 202 is low as compared with that of the elements 104 and 204 (for example, .02 w./cm./° C. as compared to .261 w./cm./° C.).

For elements of any given thermal and electrical conductivities the conversion efficiency depends strongly upon 10 the ratio of thickness of the sheath to the radius of the element or more specifically upon the cross-sectional area of the two. In the embodiments illustrated, this ratio of the radius of the elements 102 and 202 to the thickness of the sheaths 104 and 204 is preferably about 6 to 1 or more.

It is understood, of course, that the conversion efficiency of the thermocouple is also dependent upon the difference between the hot and cold junction temperatures.

20 For thermocouples utilizing a semi-metallic inner element, having a low thermal conductivity, high temperature differences can be achieved by selecting for the semi-metallic element a ratio of length to diameter, which in the exemplary embodiments herein disclosed is about 4 to 1, such that radiation transfer of heat from the surface of the inner element to the sheath establishes substantial temperature gradients within the inner element, particularly near the hot junction. When this is done, the heat flow into the inner element through the hot junction, i.e., 25 the juncture of the conical faces is exhausted to the case over the entire side wall surface of the inner element allowing the inner cold junction, i.e., the juncture of the element with the contact electrode, to assume a temperature only slightly greater than that of the outer cold junction, i.e., the juncture of the sheath and sleeve. A further consequence of such radiative cooling is the reduced electrical resistance of the semi-metallic elements, 30 said elements having a positive temperature coefficient of resistance.

35 40 The radiation responsible for the removal of the heat transmitted across the hot junction takes place between the element, its cold junction electrode, and the metal walls of the sheath and extension tube.

45 The operation of the control apparatus shown in the drawings will now be described:

As shown, pilot burner 96 is afforded fuel flow independently of control device 8 and provides a flame in heating relation to thermoelectric generator 100 and main burner 24. Also, electrically driven fan means 150 is 50 continuously energized from the source of alternating current electrical energy at 156, although, as will be readily apparent to those persons skilled in the art, switch means may be provided in circuit therewith to provide the desired control. In any event, it is necessary that 55 the pilot burner 96 be ignited and the alternating current source shown at 156 be operable to afford energization of fan means 150 before flow-control device 8 will permit fuel flow to main burner 24 as will hereinafter become apparent as the description of the operation of the control apparatus proceeds.

60 The flame at ignition burner 96 effects heating of the hot junction of generator 100 thereby effecting energization of winding 58 of electromagnetic valve operator 54 through a circuit comprising inner conductor 118 of coaxial lead 114, terminal member 144, winding 58, mounting member 52, operator housing 34 and outer conductor 116 of lead 114. The number of turns of wire and the diameter of the wire of which winding 58 is constructed must be determined, in accordance with the predetermined normal direct current output of generator 100 in 65 response to heating of the hot junction thereof by the flame at ignition burner 96, so that the ampere-turns resulting in magnet core 56 by virtue of energization of winding 58 by generator 100 is less than a first or pull-in 70 level necessary to attract armature 74 against the bias- 75

ing force of spring 70 and is also less than a predetermined lower second or drop-out level below which said energization is insufficient to hold the armature in attracted position when moved thereto. Under these conditions, it is seen that bleed port valve member 76 remains in flow-preventing engagement with bleed port member 82 thus permitting the fluid pressure within pressure chamber 42 to equal the fluid pressure at inlet 12 of valve body 10 by virtue of passageway 84. Since the pressure within chamber 42 acts upon the entire surface of reinforcing back-up plate 50 and whereas the fluid pressure at inlet 12 acts upon only a portion of the under side of valve disc 48, said valve disc 48 is retained in flow-preventing engagement with valve seat 20.

In order to move valve disc 48 to its flow-permitting position, it is necessary that electromagnetic winding 60 of valve operator 54 be energized concurrently with the aforementioned energization of electromagnetic winding 58. This requires two additional conditions. Firstly, it is necessary that the alternating current source shown at 156 effects energization of heating coil 318 of temperature varying means 316 so as to heat the hot junction of generator 200 for generation of a predetermined normal electrical potential by the latter. Secondly, it is necessary that thermostatic switch 306 respond to a given temperature condition so as to effect engagement of movable contact 314 and stationary contact 310 so that the normal electrical potential generated by generator 200 causes current to flow through winding 60 by virtue of the electrical circuit comprising inner conductor 218 of coaxial lead 214, lead wire 300, terminal 302, winding 60, mounting member 52, operator housing 34, lead wire 304 including thermostatic switch 306 and outer conductor 216 of lead 214. Such energization of winding 60 affords sufficient magnetic flux flow within magnet core 56 which when combined with the magnetic flux flow therein resulting from energization of winding 58 affords a total number of ampere-turns at or above said first or pull-in level for movement of the armature member 74 into attracted relation with respect to core member 56 against the biasing force of tension spring 70.

Such attractive movement of armature member 74 effects movement of bleed valve 76 to its flow-permitting position by virtue of clockwise pivotal movement of actuating lever 64 about the fulcrum or pivot point between bracket 62 and screw 66. Such movement of bleed valve member 76 permits the fluid pressure within pressure chamber 42 to diminish by reason of fluid flow from chamber 42 to combustion chamber 28 of heating unit 22 through the opening in bleed port member 82, the passageway between mounting member 52 and member 88 spaced therefrom, passageway 86, and bleed conduit 94. Such diminution of fluid pressure within chamber 42 continues until a point is reached where the total pressure on the upper surface of back-up plate 50 is insufficient to retain valve disc 48 in its flow-preventing position against the total force exerted on the under side of valve disc 48 by the fluid pressure at inlet 12. When this point is reached, the inlet pressure forces valve member 48 to its flow-permitting position, whereupon fluid fuel is permitted to flow to main burner 24 from inlet chamber 12, through valve seat 20, outlet chamber 14, main burner fuel supply conduit 16 and mixing chamber 26. The fluid fuel thus emitted at main burner 24 is ignited by the flame at ignition burner 96.

Burning of fuel at main burner 24 causes heating of the air within combustion chamber 28, the products of combustion being exhausted through exhaust chamber 30 and appropriate exhaust conduits. Since plenum chamber 32 is in heat exchange relation with combustion chamber 28 and exhaust chamber 30, the air within plenum chamber 32 increases in temperature and is forced to the area or space to be heated by means of the previously energized electrically driven fan means 150 which is positioned adjacent plenum chamber 32.

Thus, the air within the area or space to be heated by main burner 24 increases in temperature until the bimetal 312 of thermostatic switch 306 (positioned within such area or space) deforms sufficiently to effect disengagement of movable contact 314 and stationary contact 310. In such event, electromagnetic winding 60 is immediately deenergized, the magnetic flux flow afforded thereby within core member 56 being terminated. With electromagnetic winding 58 thus being the only winding affording magnetic flux flow in magnetic core 56, said flux flow drops to or below said lower or drop-out value and the tension spring 70 overcomes the magnetic attraction between armature member 74 and core member 56 for counterclockwise pivotal movement of actuating lever 64 about its aforementioned fulcrum. In this manner, bleed valve 76 is returned to its flow-preventing position in engagement with bleed port member 82. Such movement of bleed valve 76 interrupts further bleeding of the fluid pressure within pressure chamber 42 whereupon the pressure on back-up plate 50 is permitted to increase. Pressure continues to increase until a point is reached where the total force on back-up plate 50 is sufficient to overcome the force tending to retain valve disc 48 in its flow-permitting position, whereupon said valve disc 48 is moved to its flow-preventing position in engagement with valve seat 20 and is held in such position by virtue of the fluid pressure within chamber 42 as provided from inlet chamber 12 through passageway 84.

It may occur, that heating coil 318 is deenergized as by failure of the source of alternating current at 156 or by interruption of the energizing circuit for said winding 318. Under either of these conditions, heating of the hot junction of thermoelectric generator 200 will be interrupted and said generator 200 will no longer be able to generate the electrical potential which affords current flow through electromagnetic winding 60 as hereinbefore explained. If contacts 314 and 310 of thermostatic switch 306 are in engagement at this time, electromagnetic winding 60 is deenergized and the fuel flow to main burner 24 terminated as above set forth. In order for such operation to take place, it is necessary that deenergization of the winding 60 decrease the magnetic flux flow in core member 56 to or below said drop-out value. With present day devices, such drop-out value is generally in the neighborhood of one-half the pull-in value. In order to attain this relationship, I prefer to select the wire size and number of turns for each of the windings 58 and 60 such that the ampere-turns ratio of such windings when energized by the normal output of generators 100 and 200, respectively, is approximately 1.5 to 2.0 with winding 60 producing the greater number of ampere-turns. Under these normal conditions energization of both of the windings 58 and 60 produces sufficient ampere-turns, for example 3.5X ampere-turns to attract armature member 74 into engagement with core member 56 against the biasing force of spring 70, whereas, deenergization of only winding 60 decreases the total ampere-turns in core member 56 to something less than one-half of the ampere-turns utilized for attracting the armature, for example to 1.5X ampere-turns, whereupon spring 70 overcomes the remaining attractive force between armature 74 and core member 56, as produced by energization of only winding 58, for return of bleed port valve member 76 into flow-preventing engagement with bleed port member 82.

Should heating coil 318 be deenergized while contacts 310 and 314 are disengaged, said winding 60 will not be reenergized upon subsequent reengagement of contacts 314 and 310 wherefore sufficient magnetic flux flow in magnet member 56 will not be produced by energization of only winding 58 to move armature 74 into engagement with core member 56 and, hence, fuel will not be permitted to flow to main burner 24 upon reengagement of contacts 314 and 310 until the cause of failure of the alternating current source or the break in the energizing circuit for heating coil 318 is rectified.

It will be noted that the above-explained coordination requires that the energizing source for fan means 150 and the circuit associated therewith be in proper operating condition so that the heated air within plenum chamber 32, as afforded by main burner 24, will not be permitted to accumulate therein and create a hazardous condition. This arrangement is particularly desirable in those heating units which depend substantially solely upon electrically operated means for moving the air from the plenum chamber after it is heated by the main burner.

Should the flame at ignition burner 96 be extinguished for any reason, the hot junction of generator 100 will cool to a point where said generator 100 is incapable of generating the aforescribed normal electrical potential for energization of electromagnetic winding 58 of bleed port operator 54. However, since winding 58 when energized, produces less magnetic flux flow in core member 56 than does winding 60 when it is energized (ratio of 1.5 to 2.0 as above explained) it is seen that if winding 58 is deenergized, as by pilot flame outage, while armature 74 is in attracted position, as by simultaneous energization of both of the windings 58 and 60, the resulting loss of magnetic flux flow in core member 56, for example to 2.0X ampere-turns is insufficient to cause spring 70 to return bleed port valve 76 to its flow-preventing position. As above explained, this is due to the fact that the drop-out energization of present day devices is generally in the neighborhood of one-half the pull-in energization, for example 1.75X ampere-turns.

In view of this, I employ the tubular heat conducting member 142 on generator 100 to reverse the polarity of energization of winding 58 by said generator 100 upon outage of the flame at pilot burner 96. Upon outage of the pilot flame, not only is the temperature of the hot and cold thermojunctions of generator 100 eventually equalized, but due to the placement of tubular member 142 on sheath member 102 with respect to the hot and cold junctions of the generator, the relative temperatures thereof are reversed due to the particular heat conduction by said tubular member 142. In operation, the member 142 shields the hot junction somewhat from the heat of the flame of the pilot burner flame, whereas heat from said flame is transferred by said member to the areas of the cold junctions of the thermoelements 102 and 104, which areas store substantial heat. On outage of the pilot burner 96, the impingement of the unignited gas on the hot junction, and the relatively lower heat capacity of the hot junctions as compared with the cold junctions, causes rapid cooling of the hot junction as compared with slow cooling of the cold junctions, with resultant current reversal. In this manner, winding 58 is reversely energized so as to produce magnetic flux flow in core member 56 which bucks or opposes the magnetic flux flow therein as produced by energization of winding 60, whereupon the resultant magnetic flux flow in said core 56 is reduced to or below the predetermined lower or drop-out value which is something less than one-half the flux flow required for pull-in of the armature 74, for example to 1.25X ampere-turns and spring 70 operates to return bleed port valve 76 in its flow-preventing position in engagement with bleed port member 82. Thus the present control apparatus affords, safety shut off of fuel flow to main burner 24 upon outage of the pilot burner flame.

Should the pilot flame become extinguished while winding 60 is deenergized as by appropriate response of thermostatic switch 306, bleed port valve 76 will not be moved to flow-permitting position upon subsequent reengagement of contacts 314 and 310 of switch 306 since the magnetic flux flow produced in core 56 by energization of only winding 60 will be something less than the pull-in value of energization of electromagnetic operator 54.

In view of the foregoing, it is seen that the present invention provides control apparatus employing novel thermoelectric generator means in a particular manner whereby fuel flow to a main fuel burner is dependent

upon the presence of a pilot burner flame and satisfactory operation of an outside source of power and associated circuit means; said source of power being used for energization of electroresponsive means associated with said main fuel burner.

Although I have shown and described certain specific embodiments of my invention, I am fully aware that many modifications thereof are possible. My invention, therefore, is not to be restricted except insofar as is necessitated by the prior art and by the spirit of the appended claims.

I claim:

1. Control apparatus comprising an electroresponsive operator having a control member movable between first and second positions and having means biasing the same toward said second position, said control member being movable against said biasing means toward said first position by energization of said operator above a predetermined first level and being movable by said biasing means toward said second position whenever energization of said operator is at or less than a predetermined lower level, a source of alternating current, a first source of direct current of predetermined normal magnitude operatively related to said alternating current source and continuously operable simultaneously therewith, and a second source of direct current of predetermined normal magnitude, said first and second direct current sources being connected to energize said operator and normally operable concurrently to afford energization thereof above said first level for disposition of said control member in said first position, said first source being normally operable individually to afford energization of said operator above said lower level, and said second source being normally operable individually to at most afford energization of said operator at less than said lower level, said second source being reversible to oppose the energization of said operator afforded by said first source at least sufficiently to reduce the effective energization of said operator normally afforded by said first source to below said lower level for disposition of said control member in said second position.

2. Control apparatus comprising an electroresponsive operator having a control member movable between first and second positions and having means biasing the same toward said second position, said control member being movable against said biasing means toward said first position by energization of said operator above a predetermined first level and being movable by said biasing means toward said second position whenever energization of said operator is at or less than a predetermined lower level, a source of alternating current, a first source of direct current of predetermined normal magnitude operatively related to said alternating current source and continuously operable simultaneously therewith, a second source of direct current of predetermined normal magnitude, said first and second direct current sources being connected to energize said operator and normally operable concurrently to afford energization thereof above said first level for disposition of said control member in said first position, said first source being normally operable individually to afford energization of said operator above said lower level, and said second source being normally operable individually to at most afford energization of said operator at less than said lower level, said second source being reversible to oppose the energization of said operator afforded by said first source at least sufficiently to reduce the effective energization of said operator normally afforded by said first source to below said lower level for disposition of said control member in said second position, and circuit controlling means in circuit with said first source and said operator for controlling the energization of said operator by said first source and thereby the disposition of said control member.

3. Control apparatus for use with fuel burning equipment having a burner comprising an electroresponsive

operator having a control member movable between first and second positions and having means biasing the same toward said second position, said control member being movable against said biasing means toward said first position by energization of said operator above a predetermined first level and being movable by said biasing means toward said second position whenever energization of said operator is at or less than a predetermined lower level, a source of alternating current, a first thermoelectric generator having a thermojunction, a heater connected in continuously closed circuit with said alternating current source and continuously energized by current from said source and disposed in heating relation to said thermojunction to render said generator continuously operative to generate direct current of predetermined normal magnitude, a second thermoelectric generator of predetermined normal output, said first and second generators being connected to energize said operator and being normally operable concurrently to afford energization thereof above said first level for disposition of said control member in said first position, said first generator being normally operable individually to afford energization of said operator above said lower level, and said second generator being normally operable individually to at most afford energization of said operator at less than said lower level, said second generator having means associated therewith to render the polarity of the output thereof reversible to oppose the energization afforded by said first generator at least sufficiently to reduce the effective energization of said operator to below said lower level for disposition of said control member in said second position.

4. Control apparatus for use with fuel burning equipment having a burner comprising an electroresponsive operator having a control member movable between first and second positions and having means biasing the same toward said second position, said control member being movable against said biasing means toward said first position by energization of said operator above a predetermined first level and being movable by said biasing means toward said second position whenever energization of said operator is at or less than a predetermined lower level, a first source of direct current of predetermined normal magnitude, and a second source of direct current responsive to the flame of said burner to normally afford direct current of predetermined magnitude and of one polarity and upon outage of said flame to afford direct current of the opposite polarity, said first and second direct current sources being connected to energize said operator and normally operable concurrently during the existence of a flame at said burner to afford energization of said operator above said first level for disposition of said control member in said first position, said first source being normally operable individually to afford energization of said operator above said lower level, and said second source being normally operable individually during existence of a flame at said burner to at most afford energization of said operator at less than said lower level, said second source, on outage of said burner flame, affording a current of said opposite polarity which opposes the energization of said operator normally afforded by said first source at least sufficiently to reduce the effective energization of said operator to below said lower level for disposition of said control member in said second position.

5. Control apparatus for fluid fuel burning equipment having a main burner and a pilot burner comprising a main burner fuel valve having an electroresponsive operator and a valve member movable between open and closed positions and having means biasing the same toward closed position, said valve member being movable against the bias of said biasing means toward open position by energization of said operator above a predetermined first level and being movable by said biasing means toward closed position whenever energization of said operator is at or less than a predetermined lower level, a first source of direct current of predetermined normal magnitude, and

a second source of direct current responsive to the flame of said pilot burner to afford direct current of predetermined normal magnitude and of one polarity and upon outage of said pilot burner flame to afford direct current of the opposite polarity, said first and second direct current sources being connected to energize said operator and normally operable concurrently during the existence of a flame at said pilot burner to afford energization of said operator above said first level for disposition of said valve member in said open position and flow of fuel to said main burner, said first source being normally operable individually to afford energization of said operator above said lower level, and said second source being normally operable individually during existence of a flame at said pilot burner to at most afford energization of said operator at less than said lower level, said second source, on outage of said pilot burner flame, affording a current of said opposite polarity which opposes the energization of said operator normally afforded by said first source at least sufficiently to reduce the effective energization of said operator to below said lower level for disposition of said valve member in said closed position and shut off of the fuel to said main burner.

6. Control apparatus for fluid fuel burning equipment having a main burner and a pilot burner comprising a main burner fuel valve having an electroresponsive operator and a valve member movable between open and closed positions and having means biasing the same toward closed position, said valve member being movable against the bias of said biasing means toward open position by energization of said operator above a predetermined first level and being movable by said biasing means toward closed position whenever energization of said operator is at or less than a predetermined lower level, a source of alternating current, a first thermoelectric generator having a thermojunction, a heater connected in continuously closed circuit with said alternating current source and continuously energized by current from said source and disposed in heating relation to said thermojunction to render said generator continuously operative to generate direct current of predetermined normal magnitude, and a second thermoelectric generator responsive to the flame of said pilot burner to afford direct current of predetermined normal magnitude and of one polarity and having means associated therewith to render the polarity of the output thereof reversible upon outage of said pilot burner flame to afford direct current of the opposite polarity, said first and second generators being connected to energize said operator and being normally operable concurrently during the existence of a flame at said pilot burner to afford energization of said operator above said first level for disposition of said valve member in said open position and flow of fuel to said main burner, said first generator being normally operable individually to afford energization of said operator above said lower level, and said second generator being normally operable individually during existence of a flame at said pilot burner to at most afford energization of said operator at less than said lower level, said second generator, on outage of said pilot burner flame, affording a current of said opposite polarity which opposes the energization of said operator normally afforded by said first generator at least sufficiently to reduce the effective energization of said operator to below said lower level for disposition of said valve member in said closed position and shut off of the fuel to said main burner.

7. Fuel burning apparatus having a burner comprising a fuel valve for said burner having an electroresponsive operator having a control member movable between flow permitting and flow preventing positions and having means biasing the same toward flow preventing position, said control member being movable against said biasing means toward flow permitting position by energization of said operator above a predetermined first level and being movable by said biasing means toward flow preventing position whenever energization of said operator is at or less

than a predetermined lower level, a source of alternating current, an air circulating fan connected for energization by said alternating current source, a first source of direct current of predetermined normal magnitude operatively related to said alternating current source and continuously operable simultaneously therewith, and a second source of direct current of predetermined normal magnitude, said first and second direct current sources being connected to energize said operator and normally operable concurrently to afford energization thereof above said first level for disposition of said control member in said flow permitting position, said first source being normally operable individually to afford energization of said operator above said lower level, and said second source being normally operable individually to at most afford energization of said operator at less than said lower level, said second source being reversible to oppose the energization of said operator afforded by said first source at least sufficiently to reduce the effective energization of said operator normally afforded by said first source to below said lower level for disposition of said control member in said flow preventing position, failure of said alternating current source effecting failure of said first direct current source and movement of said control member to flow preventing position for shut-off of the fuel flow to said burner substantially simultaneously with de-energization of said circulating fan.

8. Control apparatus comprising an electroresponsive operator having first and second windings and having a control member movable between first and second positions and having means biasing the same toward said second position, said control member being movable against said biasing means toward said first position by energization of said operator above a predetermined first level and

being movable by said biasing means toward said second position whenever energization of said operator is at or less than a predetermined lower level, and first and second sources of direct current connected to energize said first and second windings respectively and having predetermined different normal output, said sources being operable concurrently to energize said windings and afford said operator energization above said first level for disposition of said control member in said first position, said first source and first winding being normally operable independently of said second source and second winding to afford energization of said operator above said lower level, and said second source and second winding being normally operable independently of said first source and first winding to at most afford energization of said operator at less than said lower level, the polarity of the direct current supplied by said second source being reversible to cause energization of said second winding by direct current of said reverse polarity in opposition to the energization of said operator afforded by said first source and first winding at least sufficiently to reduce the effective energization of said operator to below said lower level for disposition of said control member in said second position.
